UNITED STATES PATENT OFFICE.

JEAN G. AUPERIN, OF BROOKLYN, NEW YORK, ASSIGNOR TO PASSAIC METAL WIRE COMPANY, OF PASSAIC, NEW JERSEY, A CORPORATION OF NEW JERSEY.

AUTOMATIC SEAMING MACHINE.

1,364,474.

Specification of Letters Patent.

Patented Jan. 4, 1921.

Application filed July 25, 1919. Serial No. 312,310.

To all whom it may concern:

Be it known that I, JEAN G. AUPERIN, a citizen of the United States, and resident of New York city, borough of Brooklyn, 5 in the county of Kings and State of New York, have invented certain new and useful Improvements in Automatic Seaming-Machines, of which the following is a specification.

This invention relates to improvements in machines for securing the heads or bottoms upon can bodies, as by seaming the flanges of such heads and bottoms to the adjacent edges of such bodies by means of rolls revolving in contact with such flanges.

One of the objects of this invention is to provide means to automatically feed can bodies having heads or bottoms thereon in position to be operated upon by the seaming rolls for securing the flanges of the heads or bottoms to the can bodies, means for automatically holding the bodies while being seamed, and means for discharging the headed can bodies.

Another object of the invention is to provide means to automatically stop the operation of the machine in case the can bodies are fed into the machine without having heads or bottoms thereon, and to permit continued operation of the machine when the can bodies having heads or bottoms are fed or in case the operator omits to feed a can body to the machine in one of the receivers therefor.

The invention comprises novel details of improvement and combinations of parts that will be more fully hereinafter set forth and then pointed out in the claims.

Reference is to be had to the accompanying drawings forming a part hereof, wherein—

Figure 1 is a side elevation of a machine embodying this invention;

Fig. 1^a is a detail section on line 1^a, 1^a in Fig. 1;

Fig. 2 is an end view looking from the right in Fig. 1;

Fig. 3 is a plan view;

Fig. 4 is a sectional plan view on the line 4, 4 in Fig. 1;

Fig. 5 is an enlarged detail central section illustrating can holding and head seaming devices;

Fig. 6 is a similar view of parts shown 55 in Fig. 5;

Fig. 7 is a detail section on the line 7, 7 in Fig. 4;

Figs. 8, 9 and 10 are details of the can parts;

Fig. 11 is an enlarged detail, partly in section, of means for supporting and actuating the seaming or nurling rolls;

Fig. 11^a is a detail perspective of arms for said rolls;

Fig. 12 is a detail diagrammatic plan view 65 illustrating cams for operating said rolls;

Fig. 12^a is a detail section approximately on the line 12^a, 12^a in Fig. 11;

Fig. 13 is a detail section substantially on the line 13 in Fig. 3;

Fig. 14 is a detail plan view illustrating can discharging means;

Fig. 15 is an enlarged detail section on the line 15, 15 in Fig. 3;

Figs. 16 and 17 are respectively sections 75 on the lines 16, 16 and 17, 17 in Fig. 15;

Fig. 18 is a sectional detail illustrating clutch controlling parts co-operative with a head or bottom on a can;

Figs. 19 and 20 are sectional details of 80 clutch retaining parts as controlled by the parts shown in Fig. 18;

Figs. 21, 22 and 23 show the parts of Figs. 18, 19 and 20 in different positions;

Fig. 23^a is a detail perspective of the 85 clutch controlling rod of the last named figures;

Figs. 24 and 25 are enlarged detail views of arms for controlling said rod;

Fig. 26 is a plan view of part of Fig. 15;

Fig. 27 is a section on the line 27, 27 in Fig. 15.

Similar numerals of reference indicate corresponding parts in the several views.

In the accompanying drawings a suitable 95 main frame is shown in the form of a standard or pedestal 1 having an upper bracket or arm 2 and a lower bracket or arm 3. A horizontal drive shaft 4 is suitably journaled in said frame and carries a loose drive 100 pulley 5 having a clutch member 6 co-operative with a clutch member 7 keyed slidably upon said shaft, whereby the shaft may be rotated by the pulley in a well known manner. A fork 8 (Fig. 3) co-operates with 105 clutch member 7 to shift it into and out of engagement with clutch member 6 as usual. Fork 8 is shown secured to a rod 9 slideable in suitable bearings in extensions 10, 11 of frame 1 (Figs. 2, 3, 15 and 27), a spring 12 110

- coöperating with extension 10 and with an enlargement 9^a on rod 9 (Fig. 3), serving to move said rod to release clutch member 7 from member 6. Said member may be 5 placed in engagement by a bell-crank lever 13 having a fork pivotally connected with enlargement 9^a (Fig. 3) and pivoted at 14 upon frame 1 to be actuated by a rod 15 connected with a treadle 16 pivoted upon the 10 base of frame 1 (Fig. 1). When the treadle is depressed the clutch member will be engaged. A lever 17 pivoted at 18 upon extension 11 is provided with a retainer finger or projection 17^a that is adapted to engage 15 a notch 9^b in rod 9 to retain said rod set against the tension of spring 12 to retain clutch members 6 and 7 engaged for operation of the machine, (see Figs. 15 and 22). When the machine is to be started the 20 treadle 16 may be depressed to engage said clutch members and lever 17 may be manually operated to engage its finger 17^a with notch 9^b of rod 9 to retain said members in co-action for rotation of shaft 4 by pulley 5.
- 25 Means to automatically release said clutch members to stop the machine, according to certain conditions respecting the cans and their heads or bottoms, will be hereinafter described.
- 30 This machine is particularly adapted to seam the flanges of heads or bottoms 19 to cans 20 of shape other than circular by means of seaming rolls 21, 22 which rotate around in contact with the flange 19^a of said head or bottom. Devices for supporting and rotating such rolls are well known in the art, an example of which is shown in U. S. Letters Patent No. 810,245 granted to Adriance and Calleson on January 16, 1906, and 35 devices illustrated in the accompanying drawings are somewhat analogous to corresponding devices shown in said Letters Patent although the can feeding and controlling improvements hereinafter described 40 may be used with rolls operated in any other appropriate manner. Both of the rolls 21, 22 are supported by similarly arranged arms and a description of one set will suffice for both, the rolls being shown on diametrically 45 opposite sides of the can body. Each roll is pivotally carried by an arm 23 that is pivotally carried by an arm 24 by means of interposed stud or bolt 25. The arms 24 are 50 pivotally supported by studs or bolts 26 that are journaled in rotative head or disk 27, whereby the pairs of arms will be carried around therewith. Head 27 is shown 55 guided to rotate around a support 28 that is secured at its upper end to bracket arm 2, which support is shown provided with an 60 annular flange 28^a supporting and guiding recessed part 27^a of head 27, (Fig. 13). A spring 29 connected with arm 23 and head 27 tends to spread said rolls 21, 22 outwardly. The projecting end 23^a of arm 23 65 (Fig. 11^a) is coöperative with finger 30 projecting from a short shaft 31 journaled in head 27 and having arm 32 carrying roller 33 to coöperate with rotative cam member 34 (Figs. 11^a, 12, and 12^a), for controlling 70 the movements of said arms. Roller 35 on arm 24 is coöperative with a master form 36 concentric with cam member 34. The master form has a groove of shape similar to the shape of the can body and the edge 75 of flange 19^a, whereby as roller 35 travels around in said groove the rolls 21, 22 will be correspondingly guided in contact with flange 19^a for seaming it. Head 27 is provided with annular gear 37 in mesh with gear 38 secured on shaft 4, and cam member 34, shown in the form of a ring, is secured to or formed on annular gear ring 39 rotatively mounted on head 27 (Fig. 13). Gear ring 39 is in mesh with gear 40 secured on 80 shaft 4. The ratio of the gearing is such as may be desired whereby head 27 will rotate faster than cam member 34. When head 27 and cam member 34 rotate, as in the direction of arrow *a* (Fig. 12), the arms 23, 24 and rolls 21, 22, 35 will be carried around with said head and at the same time rolls 33 will coöperate with cam member 34 to cause the rolls 21, 22 to operate forcibly upon the flange of the can head for seaming the latter 95 to the body. Cam member 34 has a low part 34^a intermediate part 34^b and high part 34^c suitably disposed in extent for the roller 33 of the pair of arms 23, 24, for roller 21 and a corresponding part 34^a and high part 34^c 100 for roller 33 of the other pair of arms 23, 24 for roller 22 disposed oppositely around the cam member respecting the first named set, (Fig. 12). When the rolls 33 are operating upon low parts 34^a of cam member 105 34 the rolls 21, 22 will be spread to receive flange 19^a of the can head between them. When roll 33 of the arms of roll 21 rides upon the corresponding part 34^b the finger 30 will operate upon part 23^a of lever 23 to 110 cause roll 21 to advance with pressure against flange 19^a and when said roller 33 operates upon corresponding high part 34^c of cam member 34, said roller 21 will be forced farther against the flange. The 115 roller 33 of the other pair of arms 23, 24 will cause corresponding action of roller 22 upon the flange for finishing the same. When both rolls 33 again operate on low part 34^a 120 the rollers 21, 22 will be spread to again receive a flange between them, and so on for successive flanges.
- To feed the can bodies automatically to the seaming roll a table or disk 41 is spaced beneath said rolls and supported rigidly 125 upon arm 3, as by a hub 42, along which table the bodies will slide on edge. Spaced above said table is a rotative body feeding turret or disk 43 having a series of peripheral receivers or pockets 44 for the can 130

bodies, which receivers are adapted to bring the cans successively beneath master form 36, which is located over the arc of the receivers, with the can heads between the 5 spread rolls 21, 22. A circular guard 45 partially surrounds the turret and is spaced therefrom to admit the can bodies therebetween, which guard is secured upon table or disk 41, the upper portion of said guard 10 preferably being flared outwardly at 45^a for convenient admission of the can bodies (Fig. 7). A corresponding inner guide 46 spaced from guard 45 beneath turret 43 aids in guiding the bottoms of the can bodies (Fig. 15 7). The can bodies with their heads 19 thereon are successively placed in receivers 44 between the parts 45, 46. The turret 43 is rotated step by step to present the can bodies successively beneath master form 36, for 20 which purpose the turret is provided with a depending shaft guided in a bearing through hub 42, arm 3 and bracket arm 1^a and carrying at its lower end a disk 47, as in the general nature of a Geneva movement. Disk 25 47 is shown provided with a pair of spaced pins 48 coöperative with a disk-like member 49 having a pair of spaced threads, in the nature of a broken gear, whereby as the member 49 is rotated said threads will co-operate with said pins to impart a step by 30 step rotation to disk 47 and when the annular portion of member 49 is between two pins the disk 47 will be held stationary. The rotation of disk 47 imparts a step by step rotation to turret 43 in timed relation to the rotation of rolls 21, 22 and cam member 34. Member 49 is carried by shaft 50 journaled in bearings on the main frame, as in arm 3, and provided with a gear 51 in mesh with 35 gear 52 on shaft 53 journaled in suitable bearings as shown, shaft 53 having a spiral gear 54 in mesh with a corresponding gear or worm 55 on shaft 4. At a point of rest of the turret and beneath master form 36 is a rest 56 for the can bodies operative in a 40 recess 41^a in table 41. Rest 56 has a stem 56^a slideable in a bore 3^a in arm 3 and provided with a stop 56^b to bear upon arm 3 to limit the descent of rest 56 (Fig. 6), and at 45 an appropriate time rest 56 is raised to push the can body with its head 19 toward master form 36. A spring 57 in bore 3^a is interposed between stem 56^a and a rod 58 slideable in said bore and operated by a crank arm 59 actuated by cam 60 on shaft 50, which crank arm is pivoted at 61 upon arm 3. At the time the turret 43 comes to rest and the can body is over the rest 56 the latter is raised to push the can body toward the master form 36, and when the can head 19 has been seamed on the can body the rest 56 descends to release the can head from said master form. The master form is secured in position by a stem 62, and a rod 62^a passes 60 through said stem and master form slideable

in a bore therein and pivotally connected at its upper end to rock arm 63 pivotally supported on frame 1 at 64 and shown provided with a roller 65 operative with cam 66 secured on shaft 53 (Fig. 1). After a can has 70 been headed or seamed the cam 66 will cause arm 63 to depress rod 62^a against the can head 19, to dislodge it from the master form, the rest 56 lowering to permit descent of the can body, the rolls 21, 22 traveling around 75 the head, whereupon the turret will rotate another step to present a succeeding can with its head between the rest and master form, and so on successively. When the can with its head secured therein is passed from 80 the master form it will encounter a discharging blade 68, shown attached to guard 45 and extending to a position behind the path of the can bodies (Figs. 1, 4, 14), so that the can being advanced by the turret will encounter such blade and be discharged from the turret and from the table 41 to a suitable receptacle.

In order to hold the can bodies snugly in a lateral direction in receivers 44 of turret 90 43 while the heads are being seamed upon such bodies a presser or plunger 69 is operative in guideway 70 toward and from the can bodies (Fig. 5), which presser is shown carried by a rod 71 pivotally connected at 72 to 95 a crank arm 73 shown carried by a bracket 74 journaled in a bearing on arm 3 and having an arm 75 to which is pivotally connected a depending link 76 having a projection 77 coöperative with a cam 78 on shaft 50. 100 Each time a can is brought to rest it is positioned between rest 56 and master form 36 and the cam 78 will cause presser or plunger 69 to push against the can body and hold it firmly in receiver 44 of turret 43 (Fig. 5), 105 and when the head has been seamed upon the can body said presser will be retracted to release the body.

As so far described the machine can operate indefinitely, but in order to automatically stop the machine in case the operator should feed can bodies to the turret without having heads thereon the following arrangements are provided. To the lever 17 a control rod 79 is pivotally connected at 80 115 which rod is slideable in a bearing in arm 2 of the main frame, a spring 81 upon said rod operating against a stop 82 thereon causing said arm to operate lever 17 to release its finger 17^a from notch 9^b of rod 9. 120 Means controlled by the can bodies (or the absence thereof) serve to restrain movement of rod 79. Rod 79 has a pair of oppositely disposed notches 79^a coöperative with forked end 83^a of a retaining member 83 guided in 125 a way 84 carried by arm 2, whereby when said fork engages said notches (Figs. 16, 19) the rod 79 will be retained against the tension of spring 81 for retaining finger 17^a in notch 9^b of rod 9 to retain the clutch 130

members 6, 7 engaged for operation of the machine. Rod 79 also has a lower notch 79^b adapted to be engaged by a lower cross bar 85^a of a retaining member 85 shown 5 provided with an opening 85^b receiving rod 79 (Figs. 17, 20, 23), whereby when said bar 85^a is in notch 79^b of rod 79 the rod will be retained to prevent release of finger 17^a from rod 9 to retain the clutch members 10 in engagement for operation of the machine. When the members 83, 85 do not retain rod 79 the latter will operate lever 17 by action of spring 81 to release finger 17^a from rod 9 to permit spring 12 to cause unclutching 15 of members 6, 7 to stop the machine. The operation of the members 83, 85 is caused by the presence or absence of a can body with or without a head 19 thereon in the receiver of turret 43 at a particular position, as follows. The member 83 is pivotally connected at 86 with an arm 87 secured upon shaft 88 journaled in bearings at 89 carried by arm 2. Said shaft has an arm 90 to which is pivotally connected at 91 a 20 depending rod or member 92 reciprocative in guide 93 carried by table 41. The lower end of rod 92 is in position over the can body when the latter is brought to rest in a receiver of the turret at a position before 25 passing between the rolls 21, 22 (Fig. 3), so that said rod may be arrested from descent into the can body in case the rod encounters a can head 19 (Fig. 18). The retaining member 85 is pivotally connected at 94 with arm 95 secured to shaft 96 journaled in bearings above the bearings 89 and having an arm 97 to the free ends of which is pivotally connected at 98 a rod or member 99 having at its lower end a foot 100 adapted 30 to rest upon a can head or bottom 19 that is, on can body 20 in the last named position of said body, said rod 99 being guided by guide 93 (Figs. 1, 3, 18). To impart reciprocal movement to rods 92, 99 at the 35 proper time with respect to can bodies beneath the same and with resiliency so as not to injure the can heads or bottoms 19, an arm 101 is journaled upon shaft 96, which arm has spaced lugs 101^a (Figs. 24, 40 25), and shaft 96 has a depending finger 102 located between said lugs and opposed on opposite sides by springs 103, 104 opposing said lugs for moving said finger and shaft when the arm 101 is rocked, and for 45 permitting said arm 101 to move without moving finger 102 when foot 100 rests upon the can head. The shaft 88 also has a depending finger 105 between opposing springs like 103 and 104, between lugs 108^a 50 55 60 65 on depending arm 108 hanging from shaft 88. Arms 101 and 108 are movably connected at 101^b, 108^b with a link or rod 105 having a pin or projection 105 co-operative with a cam groove 106^a in the cam or disk 106 carried by shaft 53. The operation of

said cam causes link 107 to rock the arms 101 and 108 to cause both rods 99, 92 resiliently to be pushed toward the can head so that if the rod 92 engages the can head it will be stopped from descent. Assuming 70 a can having a head is fed into the receiver to position at the right hand side of Fig. 3, and that said can having its head is next brought beneath rods 92, 99 the operation of the cam 106 then will cause the descent of 75 rods 92, 99 against the can head so that rod 92 and foot 100 will rest thereon as in Fig. 18. The limited movement imparted by said cam to arms 87, 95 by reason of the action of springs 104, will not be sufficient to withdraw 80 fork 83^a of member 83 from notches 79^a of rod 79, nor to engage cross bar 85^a with notch 79^b so that rod 79 will be retained and clutch members 6, 7 will be kept in engagement. If a receiver 44 of turret 43 should 85 be presented beneath rods 92, 99 without a can body in said receiver then the cam 106 can move the arms 101 and 108 to actuate the levers 87, 90, 95, 97 to such an extent (because there will be no obstruction to the 90 descent of rods 92, 99), as to withdraw fork 83^a of member 83 from the notches 79^a of rod 79 and to cause the cross bar 85^a to engage notch 79^b of rod 79 to retain the rod 79 and prevent uncoupling of clutch members 6, 7 for continued operation of the machine, (see dotted lines Figs. 16, 17). In case, however, that a can body be fed to the receiver of turret 43 without a head upon such body then when such body is brought 100 to rest beneath rods 92, 99, rod 92 may descend into the can body under the influence of the operation of the cam 106 to such an extent as to draw the fork 83^a of the member 83 from notches 79^a of rod 79, and foot 105 92 will descend upon the can body (Fig. 21), sufficient to enable the rocking of the arms 95, 97, to raise the member 85 but without engaging its cross bar 85^a with notch 79^b of rod 79, whereby the latter will 110 be released and by reason of the tension of spring 81 said rod will be moved to actuate lever 17 for withdrawing its finger 17^a from notch 9^b of rod 9, whereupon spring 12 will 115 actuate said rod to uncouple clutch members 6, 7 and the machine will be stopped. When the machine is started the can bodies having heads or bottoms thereon will be fed successively to the receivers of the turret, as at the right hand position (Fig. 120 3), and as said bodies are brought to position between the master form 36 and rest 56 the body will be retained, the rolls 21, 22 at such time being spread to receive the can head therebetween. Since the head or disk 125 27 and cam member 34 rotate continuously the operation will be such that as both continue to revolve the rolls 21, 22 will operate upon the flange of the can head to seam it upon the can body, whereupon at the termi- 130

- nation of such seaming the rolls 21, 22 will spread from the seamed can head or bottom, the can body will be released by descent of rod 62^a and descent of rest 56 together with 5 withdrawal of presser 69, whereupon the turret will rotate and carry the body with the seamed head from the seaming position and present a succeeding can body and head to seaming position, the finished body being 10 discharged by blade 68 from the turret. The operation of presenting the can bodies having heads automatically step by step to the seaming rolls and discharging the headed bodies may be made continuously, except 15 that, as before stated, in case the operator should at any time feed a can body without a head to a receiver the machine will be automatically stopped before such can body is presented to the seaming position.
- 20 This invention avoids danger incident to feeding or placing cans by hand in position for operation of seaming or nurling rolls rotative around the flanges of can heads or bottoms, and affords means for feeding can 25 bodies, successively, in step by step manner, to seaming rolls expeditiously to the capacity of the machine.
- The terms "heads" as used herein is intended to refer to the closures at the ends 30 of can bodies whether they are termed "heads" or "bottoms."
- Changes may be made in the details of construction set forth without departing from the spirit of the invention as pointed 35 out in the claims.
- Having thus described my invention, what I claim and desire to secure by Letters Patent is:—
1. The combination of means for seaming 40 can bodies, means to automatically feed can bodies having heads to said seaming means, means to cause operation of the machine comprising devices coöperative with can bodies having heads thereon in the machine 45 to maintain the last named means in operation, said devices being operative to stop operation of the machine with a can body fed therein without a head on said body.
  2. The combination of means for seaming 50 can heads, means to automatically feed can bodies having heads to said seaming means, means to control the operation of the machine, and means coöperative between said controlling means and the heads on the can 55 bodies in the machine to retain said controlling means in operation when the can bodies with the heads thereon are presented in position to coöperate with the last named means, and to cause operation of the controlling means to stop the machine with a can body therein without a head on the body.
  3. The combination of means for seaming 60 can heads, means to automatically feed can bodies having heads to said seaming means, clutch means to control operation of the ma-
  - chine, a member to engage a can head on a body in the machine, and means controlled by said member to retain the clutch means in operation and to cause action of the clutch means to stop the machine in the absence of 70 a head on a can opposing said member.
  4. The combination of means for seaming can heads, means to automatically feed can bodies having heads to said seaming means, clutch means to control operation of the machine, a member to engage a can head on a body in the machine, means normally tending to disengage the clutch means, and means to retain said disengaging means from operation controlled by said member to prevent operation of the disengaging means when a can body having a head opposes said member and to permit operation of the retaining means for disengagement of the clutch means when a can body without a 80 head opposes said member.
  5. The combination of means for seaming can heads, means to automatically feed can bodies having heads to said seaming means, clutch means to control operation 90 of the machine, means normally tending to disengage the clutch means, a retainer for said disengaging means to retain the clutch means in action, a controller for said retainer, means to automatically operate the 95 controller, a member coöperative with a head on a can body in the machine, means coöperative between said member and controller for non-operation of the latter when the head on a can body opposes said member and to permit operation of said controller to actuate said retainer to cause disengagement of the clutch means when a can body without a head opposes said member.
  6. The combination of means for seaming 105 can heads, means to automatically feed can bodies having heads to said seaming means, clutch means to control operation of the machine, means normally tending to disengage the clutch means, a retainer for said 110 disengaging means to retain the clutch means in action, a controller for said retainer, means to automatically operate the controller, a retaining member coöperative with said controller to restrain its movement, a member coöperative with a head on a can body in the machine, means operative with said member to control said retaining member to cause operation of the latter to release said controller when said 115 member opposes a can body in the machine without a head on such body, said last named means comprising resiliently operating members to operate the first named member on a can head without operation of the retaining member when the first named member engages a can head.
  7. The combination of means for seaming can heads, means to automatically feed can bodies having heads to said seaming means, 120 clutch means to control operation of the ma-

- clutch means to control operation of the machine, means normally tending to disengage the clutch means, a retainer for said disengaging means to retain the clutch means in action, a controller for said retainer, means to automatically operate the controller, a retaining member coöperative with said controller to restrain its movement, an arm connected with said retaining member, a member connected with said arm to oppose a head on a can body in the machine, and means operated by the machine to actuate said arm to cause said member to engage a can head without operation of the retaining member and to cause operation of the retaining member when said member opposes a can without a head thereon.
8. The combination of means for seaming can heads, means to automatically feed can bodies having heads to said seaming means, clutch means to control operation of the machine, means normally tending to disengage the clutch means, a retainer for said disengaging means to retain the clutch means in action, a controller for said retainer, means to automatically operate the controller, a retaining member coöperative with said controller to restrain its movement, an arm connected with said retaining member, a member connected with said arm to oppose a head on a can body in the machine, means comprising resilient members operative by the machine to actuate said arm through said resilient members to cause said member to engage a can head without operation of the retaining member and to cause operation of the retaining member through said resilient members when said member opposes a can without a head thereon.
9. The combination of means for seaming can heads, means to automatically feed can bodies having heads to said seaming means, clutch means to control operation of the machine, means normally tending to disengage the clutch means, a retainer for said disengaging means to retain the clutch means in action, a controller for said retainer, means to automatically operate the controller, a retaining member coöperative with said controller to restrain its movement, an arm connected with said retaining member, a member to oppose a head on a can body in the machine, an arm connecting said member and the first named arm, a finger connected with said arm, another arm adjacent to said finger, springs interposed between said arm and finger, a link connected with said last named arm and a cam coöperative with said link to rock the last named arm to permit said member to engage a can head without operating the retaining member and to operate the retaining member to release the controller when said member opposes a can body without a head thereon.
10. The combination of means for seaming can heads, means to automatically feed can bodies having heads to said seaming means, clutch means to control operation of the machine, means normally tending to disengage the clutch means, a retainer for said disengaging means to retain the clutch means in action, a controller for said retainer, means to automatically operate the controller, a retaining member having a fork adapted to coöperate with notches in the controller to restrain its movement, an arm connected with said retaining member, a member to oppose the head on a can body in the machine, an arm connecting said member and the first named arm, a second retaining member having a part coöperative with a notch in the controller to restrain its movement, a third arm connected with the second retaining member, a second member to oppose the head on a can body in the machine, an arm connecting the second member with the third named arm, fingers connected with said first and third arms, a cam, arms operatively connected with said cam, and springs interposed between the last named arms and said fingers whereby said members will be moved toward said head on said can without operating the corresponding retainer when the said members engage said can head and for causing release of the controller when a can body opposes said members without a head on said body.
11. The combination of means for seaming can heads, means to automatically feed can bodies having heads to said seaming means, clutch means to control operation of the machine, means normally tending to disengage the clutch means, a retainer for said disengaging means to retain the clutch means in action, a controller for said retainer, means to automatically operate the controller, a retaining member having a fork adapted to coöperate with notches in the controller to restrain its movement, an arm connected with said retaining member, a member to oppose the head on a can body in the machine, an arm for connecting said member and first named arm, a second retaining member having a part coöperative with a notch in the controller to restrain its movement, an arm connected with the second named retaining member, a second member to oppose a head on a can body in the machine, an arm for connecting the second member with the third named arm, fingers connected with the first and third named arms, a cam, arms 101 and 108 operatively connected with said cam, said arms having lugs opposing the respective fingers, springs interposed between the fingers and the cor-

responding opposing lugs for resiliently moving either of said members toward said head on a can body without operating said retaining members to release the controller, 5 one said springs serving to move one of said retaining members to release the controller when a can body without a head opposes said members.

12. The combination of means for seam-
10 ing can heads, means to automatically feed can bodies having heads to said seaming means, clutch means to control operation of the machine, means normally tending to dis-
engage the clutch means, a retainer for said
15 disengaging means to retain the clutch means in action, a controller for said re-
tainer, means to automatically operate the controller, a retaining member coöperative with said controller to restrain its move-
20 ment, an arm connected with said retaining member, a member connected with said arm

to oppose a head on a can body in the machine, means comprising resilient members operative by the machine to actuate said arm through said resilient members to cause 25 said first named member to engage a can head to prevent operation of the retainer, a second member having a foot to engage a can body without a head thereon, a second retaining member coöperative with the controller to restrain it, and means comprising resilient devices operative by the machine to actuate the second member to cause the second named retaining member to permit the controller to operate for stopping the 30 machine when a can body having no head thereon opposes said foot.

Signed at New York in the county of New York and State of New York this 24th day of July A. D. 1919.

JEAN G. AUPERIN.
